UNITED STATES PATENT OFFICE.

HERMAN J. HUISKAMP, OF FORT MADISON, IOWA.

HEEL-TRIMMING MACHINE.

SPECIFICATION forming part of Letters Patent No. 324,844, dated August 25, 1885.

Application filed November 10, 1884. (No model.)

To all whom it may concern:

Be it known that I, HERMAN J. HUISKAMP, of Fort Madison, in the county of Lee and State of Iowa, a citizen of the United States, have invented a new and useful Improvement in Heel-Trimming Machines, of which the following is a full, clear, and exact description, reference being had to the accompanying drawings, forming a part of this specification

10 in explaining its nature, in which—

Figure 1 shows my invention applied to a portion of the heel-trimming machine known as the "King heel-trimming machine," shown and described in Letters Patent No. 267,544, dated November 14, 1882. Fig. 2 is an enlarged sectional view of a portion of the cutter-head guide and cutters with a boot-heel in position to more clearly show the construction and operation of my improvement. Fig. 3 20 represents in perspective the shape of the knife, which constitutes the especial feature of my invention. Fig. 4 is a section upon the line xx of Fig. 3. Fig. 5 is a view in rear elevation of the gage-plate, representing a guide and guard having a lip which partially covers the point of the finishing-knife. Fig. 6 is a view in elevation of the feathering and trimming knives.

The object of the invention is to provide 30 means for what is commonly known as "feather-edging" the heel—that is, the removal of a slight skiving from the upper edge of the heel-portion of the outsole—in order to provide a form of finish which is at the present time 35 much in vogue.

All the parts which are shown in the drawings, with the exception of the feather-edging knife and the removable guide and guard, hereinafter described, and the variations in 40 the form of the heel-shaving knife, also hereinafter specified, are the same as those described in the said Patent No. 267,544.

Referring to the drawings, A is the cutter-head, having the shaving knives or cutters, 45 which are positively revolved, and are secured to the head and provided with the adjustments as described in said patent. B is a portion of the jack which permits all necessary adjustments of the boot or shoe heel in relation to 50 the cutters, and is the same as that described in said patent. C represents what is called the "gage-plate" in said patent. As, however,

my invention contemplates not only the trimming of the heel, but also the trimming of the upper edge of the sole about the heel, it is 55 necessary that the gage C should be somewhat differently constructed from that of the patent. Before describing this difference I will describe the feather-edging or sole edge-trimming knife and the way which I prefer to 60 secure it to the cutter-head.

The best illustration of the knife is that found in Fig. 3 of the drawings; and it comprises a flat plate, D, having on one edge a backward extension, d , in the form of a half-dovetail, between the lower portion, d' , of which and the back of the knife or plate is the groove or recess d'' , which receives the projection d^3 , also in the form of a half-dovetail, on the trimming-knife D', and the section d' also 70 closes into a recess in the edge of the knife D'. In other words, the plate D is locked to the knife D' by a half-dovetail construction, whereby one portion of one plate overlaps a portion of the other plate, so that the two knives or 75 plates are held firmly together. Extending forward from the outer edge of the plate D, in line with the extension d , is the sole-edge-skiving knife d^3 . This knife extends to a point, d^5 , and has the cutting-edge d^6 extending back 80 therefrom, having the bevel surface d^7 ; and the cutting-edge of this sole-edge-skiving knife, when in use, projects slightly in advance of the cutting-edge d^8 of the heel-trimming knife D'. 85

Both the plate D and the knives D' have a slot, d^9 , of the same size, location, and shape, so that both plates may be fastened to the cutter-head by one bolt; and the plate D is arranged to slide in relation to the knife D', so 90 that as the cutting-edges of the knives wear they may be adjusted in relation to each other, or the sole-edge-skiving knife may be adjusted in or out in relation to the cutting-edge of the heel-trimming knife, or may shave narrower 95 or wider skivings from the sole-edge, as may be required or desirable.

In order that the point of the sole-edge-skiving knife may not come in contact with the upper and injure it, I have arranged upon 100 the edge of the gage-plate C the lip c , which extends slightly downward from the removable plate c' , forming a part of the gage-plate and fastened to it by the screws c^2 . This lip

also projects outward from the inner edge of the gage-plate to cover the point of the knife d' . In use this lip enters, or partially enters, the space between the sole-edge and the lower portion of the upper, and it thus answers not only as a protector or guard, but also as a guide in governing the presentation of the sole-edge, as well as the heel, to the trimming-knives.

I form the lip upon the removable plate c' , 10 instead of upon a gage-plate, as it will be necessary to remove them from time to time as they are worn out and substitute others; also because of the necessity of changing the form and depth of the lip from time to time to 15 adapt the machine to different styles and varieties of work.

It is not necessary that there be more than one sole-edge skiving or feathering knife on each cutter-head.

20 Of course I do not confine the use of this invention to the machine described, but intend to employ it on any heel-trimming machine having rotary cutters.

In operation the heel is presented to the 25 cutters in the same manner as it is to the cutter of the King rotary machine, and the heel is not only trimmed upon its vertical edge, but its upper edge is also beveled.

Having thus fully described my invention, 30 I claim and desire to secure by Letters Patent of the United States—

1. In a heel-trimming machine, the combination of the blade or cutter D' with the plate D , supporting the edge skiving or feathering knife, all substantially as and for the 35 purposes described.

2. The combination, in a heel-trimming machine, of a rotary shaving knife or blade, D' , and the plate D , adjustable upon the knife D' and supporting the sole-edge skiving or 40 feathering knife d' , all substantially as and for the purposes described.

3. The combination of the shaving-knife D' and the sole-edge skiving or feathering knife plate interlocked by the half-dovetail d d' , as 45 described, all substantially as and for the purposes set forth.

4. In a heel-trimming machine, the feathering-knife d' , having the cutting-edge d'' and the bevel surface d' , all substantially as and 50 for the purposes described.

5. In a heel-trimming machine, the combination of the gage-block C with the removable guard or gage plate c' , all substantially as and for the purposes described.

HERMAN J. HUISKAMP.
